SHUTTLE

Alyre Roy and Anthony Cortina, New London,
Conn.; said Roy assignor to Estelle G. Gruskin,
New London, Conn.

Application June 25, 1935, Serial No. 28,361

1 Claim. (Cl. 139—210)

The present invention relates to new and useful improvements in loom shuttles and has for its primary object to provide, in a manner as hereinafter set forth, a device of this character comprising a spindle including a novel construction and arrangement for automatically securing the quill firmly in position when said spindle is swung downwardly into the shuttle but which will permit ready removal of said quill when said spindle is swung upwardly out of said shuttle.

Other objects of the invention are to provide a shuttle of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view partially in side elevation and partially in vertical longitudinal section of a shuttle constructed in accordance with the present invention, showing the spindle in raised position.

Figure 2 is a view in top plan of the invention, showing the spindle in lowered or operative position, the quill being shown in section.

Figure 3 is a view in vertical transverse section, taken substantially on the line 3—3 of Figure 2.

Figure 4 is a view in vertical transverse section, taken substantially on the line 4—4 of Figure 2.

Figure 5 is a vertical sectional view, taken substantially on the line 5—5 of Figure 1.

Figure 6 is a view in vertical longitudinal section through one end portion of the shuttle, taken substantially on the line 6—6 of Figure 2.

Figure 7 is a horizontal sectional view, taken substantially on the line 7—7 of Figure 1.

Figure 8 is a horizontal sectional view, taken substantially on the line 8—8 of Figure 1.

Referring now to the drawings in detail, it will be seen that the embodiment of the invention which has been illustrated comprises a body 1 of the usual shape, said body being substantially hollow. Traversing one end portion of the body 1 is a pin 2 upon which a spindle 3 is mounted for swinging movement in a vertical plane into and out of the body 1. Extending longitudinally into the spindle 3 from its pivoted end

to a point adjacent its free end is a split 4 providing bifurcations 5. The bifurcations 5 are slideable as well as rotatable on the pin 2. Further, the bifurcations 5 are resilient, the tendency thereof being to spring together. The spindle 3, of course, is to receive the usual quill 6. Also traversing the aforementioned one end portion of the body 1, adjacent the pin 2, is a stop 7 upon which the spindle 3 rests when in lowered or operative position, as illustrated to advantage in Figure 6 of the drawings.

The reference numeral 8 designates a longitudinal socket in the body 1 which communicates with the spindle receiving chamber 9 of the shuttle at the end thereof in which the pin 2 is located. The socket 8 slidably receives a stem 10 which projects into the chamber 9 and which carries a plate 11. Projecting from the plate 11 is a cam 12 which is engaged between the pivoted end portions of the bifurcations 5 of the spindle 3. The cam 12 is substantially wedge-shaped as shown to advantage in Figures 4 and 5 of the drawings. A coil spring 13 in the socket 8 yielding urges the cam 12 into operative engagement with the spindle 3. The upper portions of the pivoted end portions of the bifurcations 5 are recessed, as at 15, (see Figure 4) to permit the spindle 3 to contract when swung to raised position.

It is thought that the operation of the invention will be readily apparent from a consideration of the foregoing, particularly to those skilled in the art to which the device pertains. When the spindle 3 is swung to raised position, as seen in Figure 1 of the drawings, the recesses 15 receive the cam 12, thus permitting said spindle 3 to contract and allowing the quill 6 to be easily slipped thereon or removed therefrom. When the spindle 3, with the quill 6 mounted thereon, is swung downwardly into the shuttle to operative position, the cam 12 spreads the bifurcations 5 in a manner to firmly bind said quill in position, as best seen in Figure 3 of the drawings. The yieldingly mounted plate 11 rides on the pivoted end portions of the bifurcations 5 and is engaged therewith in a manner to releasably secure the spindle 3 in either its raised or its lowered position.

It is believed that the many advantages of a shuttle constructed in accordance with the present invention will be readily understood, and although a preferred embodiment of the device is as illustrated and described, it is to be understood that changes in the details of construction and in the combination and arrangement of parts

may be resorted to which will fall within the scope of the invention as claimed.

What is claimed is:—

- A shuttle comprising a body having a chamber therein and further having a socket therein communicating with the chamber, a pin traversing the chamber, a spindle, said spindle including resilient bifurcations rotatably and slidably mounted on the pin, a stem extending slidably into the socket, a plate on one end of said stem, a substantially wedge-shaped cam on the plate en-

gaged between the bifurcations for spreading said bifurcations when the spindle is swung to operative position in the chamber, and a coil spring in the socket engaged with the plate for yieldingly urging the cam between the bifurcations, said plate riding on the pivoted end portions of the bifurcations and being engaged therewith for releasably securing the spindle in operative or inoperative position. 5

ALYRE ROY.
ANTHONY CORTINA.
